UNITED STATES PATENT OFFICE.

ARTHUR B. JOHNSON, OF LAS ANIMAS, COLORADO.

ROTARY ENGINE.

1,378,415.

Specification of Letters Patent. Patented May 17, 1921.

Application filed February 14, 1920. Serial No. 358,799.

To all whom it may concern:

Be it known that I, ARTHUR B. JOHNSON, a citizen of the United States, residing at Las Animas, in the county of Bent and State 5 of Colorado, have invented certain new and useful Improvements in Rotary Engines, of which the following is a specification.

This invention relates to improvements in rotary engines having novel means for utilizing steam pressure as a source of power.

An important object of this invention is to provide a rotary engine having a pair of coacting rotors and novel means for directing steam or other motive fluid into contact 15 with the rotors a plurality of times, thereby resulting in a more economical operation of the engine.

A further object of the invention is to provide a rotary engine which is of highly simplified construction, simple in use and comparatively economical to operate at a variety 20 of speeds.

Other objects and advantages of this invention will be apparent during the course 25 of the following description.

In the accompanying drawings forming a part of this application and in which like numerals are employed to designate like parts through the same:

30 Figure 1 is a central vertical section through a rotary engine embodying the invention,

Fig. 2 is a horizontal section through the same,

35 Fig. 3 is a side elevation of the same,

Fig. 4 is a diagrammatical view of the casing illustrating the arrangement of the several high and low pressure receivers.

In the drawings wherein for the purpose 40 of illustration is shown a preferred embodiment of the invention, the numeral 10 generally designates a base which may be attached through the medium of bolts 11 to a floor or other support. A pair of legs or standards

45 12 extend upwardly from the base and form a support for a rotor housing or stator 13. The stator or casing 13 is provided on opposite sides with rotor heads 14 and 15 which conform in configuration to the stator and

50 are secured to the same by fastening means 16 preferably in the form of bolts. The rotor heads 14 and 15 are each provided with a pair of spaced bosses 17 arranged outwardly of and surrounding openings 18

55 through which are extended power shafts 19. As illustrated particularly in Fig. 2, an an-

nular packing gland 20 is secured within each boss 17 by a sleeve nut 21 having threaded engagement with and adjustable within said bosses. The glands 20 obviously 60 serve as a means for preventing the leakage of fluid pressure from the interior of the stator.

The rotor head 14 is provided with a plurality of spaced outwardly extending brackets or arms 22 forming a support for a laterally extending plate or bridge 23. The end portions of the bridge 23 are provided with bearings 24 which may be formed from a pair of semi-circular sections held in position by cap screws 25. The bearings 24 may be of any suitable anti-friction metal. Each shaft 19 has a gear 26 keyed or otherwise secured thereon and meshing with the gear of the other shaft so that both of the shafts 70 will be operated together.

As illustrated in Fig. 1, the shafts 19 are provided with rotors 27 and 28 secured in position by keys 29 which fit within opposed keyways 30 and 31 in the shafts and the 80 rotors. Each rotor is provided with a plurality of radially arranged spaced blades 32 which have their edge portions 33 and their end portions 34 extended inwardly so as to provide bucket blades. As illustrated particularly in Fig. 1, the axes of the rotors 28 and 29 are arranged in spaced parallel relation and therefore the blades 32 are caused to interlock at the point where the rotors are arranged the closest together. This interlocking of the blades does 90 not, however, cause the blades to contact so that the rotors may operate without an appreciable amount of drag or friction. As illustrated in Fig. 1, the periphery of each 95 rotor is provided between the blades with concave recesses to receive the outer portions of the blades of the other rotor whereby leakage of steam past the blades is reduced to a minimum. Motive steam is injected into 100 contact with the blades through high pressure nozzles 35 in the rotor heads 14 and 15. The nozzles 35 are arranged slightly above the shafts 19 and discharge the steam 105 against the blades at a slight angle to the same. As the steam is injected into the casing on opposite sides of the same, the rotors are prevented from binding against either of the rotor heads 14 or 15. The casing 13 is provided with a downwardly extending 110 pointed steam cut-off 36 arranged directly above the steam nozzles 35 and adapted to

direct the steam after being injected into the casing into contact with the blades of each rotor with equal pressure.

During the movement of the high velocity steam about the rotor 27, a portion of the same is injected into a high pressure receiver 37 formed in the rotor head 14. As illustrated in dotted lines in Fig. 3, the high pressure receiver 37 is of arcuate formation and conforms to the curvature of the periphery of the rotor 27 and is provided with a high pressure nozzle 38 which discharges the steam from the receiver at an angle into contact with the blades a second time. The pressure of the steam is, of course, reduced upon leaving the receiver 37 but a more uniform movement of the rotor is insured by so conveying the steam. By this construction the economy with which the engine may be operated is materially increased. All of the steam does not, however, enter the receiver 37 but a portion of the steam continues to act on the blades 32.

When the steam leaves the nozzle 38 of the high pressure receiver 37, the same is of course brought into contact with the radial blades 32 and is subsequently directed into a low pressure receiver 39 in the rotor head 15. With reference to Fig. 3, it will be noted that the low pressure receiver 39 is curved longitudinally and is provided with a discharge nozzle 40 which directs the steam from the receiver into contact with the blades a third time. A plurality of spaced stationary guides or blades 42 are arranged at the entrance to the low pressure receiver 39 and serve to direct the steam into the receiver 39. Finally the steam is discharged into exhaust chambers 43 from where it is conveyed through an exhaust pipe 44 threaded or otherwise secured to an interiorly screw threaded extension 45 in communication with the exhaust chambers 43.

The steam directed against the blades of the rotor 28 is also conveyed through a high pressure receiver 37 formed in the rotor head 15 and discharging against the blades of the rotor at a somewhat reduced pressure. The arrangement of the high and low pressure receivers for the rotor 28 will be the reverse from that of the rotor 27. Upon leaving the discharge jet 38 of the receiver formed on the rotor head 15, the steam is again directed into contact with the rotor. The low pressure receiver 39 of the rotor 27 is formed on the rotor head 14 so that the steam is caused to traverse the blades in entering said receiver 39. As particularly illustrated in Fig. 3, the steam is discharged from the low pressure receiver and contacts with the blades just prior to entering the exhaust

port 43 along with the steam which did not enter the last receiver.

A motor constructed in accordance with this invention will be characterized by the noticeable absence of vibration due to the fact that the pressure on the rotors is maintained substantially uniform throughout the rotation of the rotors.

It is obvious that a motor constructed in accordance with this invention may have its parts arranged in a manner to give the best results under given conditions. More particularly it might be stated that the number of blades and the size of the rotors may be varied according to the conditions under which the engine operates and according to the size of the same. For instance, in a high speed engine the blades will of necessity be closer together and an increased number of steam jets will be provided about the rotors.

It is to be understood that the form of the invention herewith shown and described is to be taken as a preferred embodiment of the same and that such minor changes in construction and arrangement of parts may be made as will remain within the spirit of the invention and the scope of what is claimed.

Having thus described the invention, what is claimed as new is:

1. The combination with a casing having a pair of rotor heads, of steam supply jets formed on said rotor heads and discharging at an angle to said rotors, and a downwardly extending pointed dividing member arranged between the upper portions of said rotors.

2. The combination with a casing having a pair of rotor heads, of steam supply jets secured to said heads on opposite sides of said casing, rotors arranged within said casing and having interlocked spaced blades, a high pressure receiver for each rotor, and a low pressure receiver for each rotor.

3. The combination with a casing having a rotor head on each side, of rotors having radial blades, shafts supporting said rotors, means connecting said shafts, steam supply jets carried by said rotor heads, arcuate receivers formed in said rotor heads and having inlet and discharge means, a second set of receivers formed in the rotor heads and having inlet and discharge means in communication with the interior of the casing, stationary guides carried by the second-named receivers at the inlet ends of the same, and a dividing member arranged adjacent said steam supply jets.

In testimony whereof I affix my signature.

ARTHUR B. JOHNSON. [L. S.]
